[57] CLAIM

The ornamental design for a suture package, as shown and described.

DESCRIPTION

FIG. 1 is a perspective view of a suture package showing my new design, shown in open position;

FIG. 2 is a perspective view thereof;

FIG. 3 is a perspective view thereof, shown in partially folded position;

FIG. 4 is a perspective view thereof, shown in a further partially folded position;

FIG. 5 is a perspective view thereof, shown in a further partially folded position;

FIG. 6 is a perspective view thereof, shown in a further partially folded position;

FIG. 7 is a perspective view thereof, shown in a completely folded position;

FIG. 8 is a perspective view thereof, shown in open position; and,

FIG. 9 is a perspective view thereof, shown in partially folded position.

The broken line showing of the fold lines, sutures and forceps tips in the FIGS. 1 through 9 are for illustrative purposes only and forms no part of the claimed design.
